UNITED STATES PATENT OFFICE.

HAROLD B. WINCHELL, OF COLUMBUS, OHIO, ASSIGNOR TO THE JOHN W. BROWN MFG. CO., OF COLUMBUS, OHIO, A CORPORATION OF OHIO.

FOCUSING MEANS FOR VEHICLE HEAD LAMPS.

Application filed July 2, 1927. Serial No. 203,036.

This invention relates broadly to improvements in vehicle head lamps, and with reference to the more specific application thereof, is particularly directed to an improved mechanism for effecting the support of the incandescent bulbs of such lamps so that the latter may be adjusted advantageously to procure the desired focal relationship between the bulbs and the associated reflectors.

10 The invention has for one of its principal objects the provision of a focusing mechanism by means of which the lamp bulb may be longitudinally adjusted in the principal axis of the reflector and, in addition, may be adjusted 15 in a plane perpendicular to the plane of longitudinal adjustment, the arrangement permitting the light source or filament of the bulb to be very carefully regulated in its operative relationship with respect to the reflector so as to secure a projected light beam 20 of proper spread, direction and controlled dispersion.

With these and other objects in view, as will appear as the description proceeds, the 25 invention consists in the novel features of construction, combinations of elements and arrangements of parts hereinafter to be more fully described and pointed out in the appended claims.

30 In the accompanying drawing:

Figure 1 is a view in side elevation of a vehicle head lamp, the casing of the latter being broken away and disclosed in section to set forth the internal mechanism,

35 Figure 2 is a plan view, partly in horizontal section, of the improved bulb supporting and focusing mechanism comprising the present invention,

Figure 3 is a vertical longitudinal sectional view on the line 3—3 of Figure 2,

Figure 4 is a transverse vertical sectional view on the line 4—4 of Figure 2,

Figure 5 is a similar view on the line 5—5 of Figure 2.

45 Referring more particularly to the drawings the numeral 1 designates the casing of a vehicle head lamp. Arranged within the casing is the usual type of reflector 2. The axial portion of the reflector is provided with a 50 rearwardly extending tubular boss 3, provided with longitudinally extending slots 4 in the opposite sides thereof.

55 Adjustably positioned within the boss 3 in a tubular bulb socket member 5, in the forward end of which is removably positioned

the base of a lamp bulb 6, the latter being of the usual type employed in lamps of this character. The socket member is provided with the usual bayonet slots 7, which receive pins on the base of the bulb and provide the customary connection for uniting the bulb with the socket member. The socket member is further provided with the usual insulated disks 8 and 9, the latter being separated by a spring 10, the disk 8 being stationarily mounted in the rear end of the socket member and the disk 9 loosely mounted for sliding movement in said member and is retained in engagement with the base of the bulb by the spring 10. Openings are provided in the 60 disks 8 and 9 permitting of the passage of the current conveying wires (not shown) to the base of the bulb.

The socket member 5 is provided with laterally directed transversely aligned studs 11, 75 which are slidably received within the slots 4, and have their outer ends received within openings 12 provided in the yoke shaped ends 13 of an adjusting bar 14. This bar extends longitudinally and rearwardly of the lamp 80 as shown in Figure 1, and the rear end thereof terminates in a downwardly directed ear 15, which is formed with a threaded opening for the reception of the shank of an adjusting screw 16. This screw is rotatably mounted 85 in an opening provided in the rear wall of the casing 1, and the headed end thereof is arranged exteriorly of the casing where it is conveniently accessible. By rotating the screw it will be apparent that longitudinal 90 movement will be imparted to the bar 14, and since the latter is directly connected with the socket member through the medium of the studs 11 it follows that the longitudinal adjustment of the bars will impart corresponding adjustment to the bulb supported in the socket member, whereby said bulb may be adjusted longitudinally with respect to the principal axis of the reflector. Preferably, a spring 17 surrounds the screw 16 and is situated between the ear 15 and the back of the casing. The spring 17 serves to maintain the adjustment of the bar which is secured by the medium of the screw.

In order to procure adjustment of the lamp bulb in a plane perpendicular to that obtained by the bar 14, the socket member 5 terminates in an integral U shaped frame 18, the rear portion of which being formed to constitute a circular head as shown in Figure 110

5, said head being indicated by the numeral 19. The latter, in this instance, is formed to include a transversely disposed slot 20 which receives a pin 21 carried by the forward end 5 of an adjusting shaft 22. As shown in Figures 2 and 5, the pin 21 is arranged eccentrically with respect to the longitudinal axis of the shaft 22, and it will be seen that when said shaft is rotated the eccentricity of the pin 21 10 will cause oscillation on the part of the socket member about the axis of the stud 11. This is indicated by dotted lines in Figure 3.

The shaft is supported for rotation at its rear end in an opening provided in the rear 15 wall of the casing 1, while the forward end of said shaft is supported for rotation in an opening provided in an upstanding ear 23 formed with the bar 14. A coil spring 24 surrounds the rear end of the shaft 22 and has 20 its forward end seated in an annular groove provided in said shaft as at 25. This arrangement confines the spring 24 between the groove 25 and the rear wall of the casing, 25 maintaining said spring under compression so that the same will exercise sufficient frictional pressure on the walls of the groove 25 to maintain the shaft 22 in any of its adjusted positions.

In operation, by adjusting the screw 16 30 longitudinal travel will be imparted to the bar 14, and corresponding movement will be imparted to the socket member 5 and the bulb supported thereby by reason of the studs 11. In cross-section the studs 11 are of rectangular formation, however, the openings 35 12 in the forward end of the bar 14 are circular and while this permits of rocking movement on the part of the socket member yet longitudinal adjustment of the bar 14 will result in imparting corresponding adjustment 40 to said socket member. The adjustment of the socket member in a longitudinal plane is thus secured by the medium of the bar 14 and the retention thereof in such adjusted positions by the action of the spring 17. Then, 45 through the medium of the shaft 22 and the eccentric pin 21 on the forward end thereof adjustment of the socket member in a perpendicular plane is obtained. The rotation 50 of the shaft results in oscillating the socket member about the horizontal axis of the studs 11 and this results in swinging movement of the bulb in a vertical plane. The compound adjustment thus provided enables the lamp 55 filament to secure the most advantageous positions in relation to the reflector 2, producing a resulting light beam of proper spread, distribution and form, producing a stronger

and better directed driving light, the elimination of vagrant or uncontrolled light rays 60 and the corresponding reduction in obnoxious lamp glare. The construction has the advantage of mechanical simplicity, economy in manufacture and facility and permanence 65 in adjustment.

What is claimed is:

1. In a vehicle head lamp, a casing, a reflector mounted within said casing and including an axially disposed rearwardly extending slotted boss, a socket member provided with transversely extending studs movably positioned within said boss with the studs projecting through the slots therein, an adjusting bar provided with a yoke at the forward end thereof having openings formed 70 therein for the reception of said studs, a screw carried by the rear end of said casing and engaging with said bar to adjust the latter longitudinally, and a rotatable shaft journaled in connection with said casing and said bar, the forward end of said shaft being provided with an eccentrically disposed pin received within a slot provided in the rear portion of said socket member, said pin serving 75 upon the rotation of said shaft to oscillate 80 said socket member about the axis of the studs.

2. In a vehicle head lamp, a casing, a reflector mounted within said casing and formed to include an axially disposed rearwardly extending boss, a socket member movably positioned within said boss, trunnions projecting laterally from said socket member and slidably received within slots provided in said boss, an adjusting frame having the forward end thereof provided with openings 90 in which said trunnions are received, a screw connection between the rear end of said frame and said casing operating to effect longitudinal adjustment on the part of said frame and said socket member, a shaft rotatably journaled in connection with said frame and said casing, a pin formed upon the forward end of said shaft and disposed in eccentric relationship with respect to the longitudinal axis of the shaft, said pin being receivable within a slot provided in the rear of said socket member, whereby upon the rotation of said shaft said socket member may be oscillated 95 about the axis of said trunnions, and spring means cooperative with said shaft and said frame for maintaining the latter in their various positions of adjustment.

In testimony whereof I affix my signature.

HAROLD B. WINCHELL.
